UNITED STATES PATENT OFFICE.

EDWIN E. PORTER, OF CANAL FULTON, OHIO.

APPARATUS FOR THE TRANSMISSION OF POWER.

SPECIFICATION forming part of Letters Patent No. 429,153, dated June 3, 1890.

Application filed March 7, 1890. Serial No. 343,010. (No model.)

To all whom it may concern:

Be it known that I, EDWIN E. PORTER, a citizen of the United States, residing at Canal Fulton, in the county of Stark and State of Ohio, have invented certain new and useful 5 Improvements in Apparatus for the Transmission of Power, of which the following, with the accompanying drawing, is a specification.

10 My invention relates to apparatus wherein brush-wheels are used for transmitting power.

15 The object of the invention is to provide simple and effective means for adjusting such wheels for various speeds and firmly securing the brush-wheel in any desired position; and, further, to provide for reversing the direction of the power transmitted by such wheels.

20 In view of these objects my invention consists in the construction, arrangement, and combination of parts shown and described herein, and pointed out in the claims.

25 The drawing is an elevation, partly in section, of my improved apparatus.

30 A is the driving-pulley, having an elongated turned hub B, which has a vertical movement in the bearings C C', said pulley also having a solid disk D, as shown. Said pulley, hub, and disk are preferably made integral with each other.

35 E is the counter-shaft, having mounted thereon the pulley F, from which runs a belt to the machine to be driven. There is also mounted on the counter-shaft a brush-wheel H, which wheel is designed to have frictional contact with the disk D. A groove or keyway e is cut along one side of the counter-shaft E, and the wheel H is keyed to said shaft by a 40 key h in such manner as that said wheel may be shifted along the counter-shaft under the disk D to each side of its center, and will rotate the counter-shaft as the said wheel H is driven by the disk D.

45 M in the drawing represents the framework designed to support said shaft and wheels. To the frame-work is pivoted a lever G in the eye or hook of the strap I. Said lever embraces the upper end of the hub 50 B, as shown at g, and to the outer end of said lever G is attached the arm K, which con-

ncts with the eccentric L. Said eccentric is secured to the frame-work M in any suitable manner. The eccentric L is provided with an arm N, rigidly secured thereto. To the outer end of the arm N is attached the vertical bar O by any suitable universal joint n. Said bar O is supported by suitable guides o, which will allow a vertical and also a rotary motion of the bar O. At the bottom of the bar O is secured a handle P at right angles thereto. A lateral lever Q is secured to the bar O. To the outer end of said lever Q is attached a rod S, having a yoke R on its opposite end, and which yoke carries a 65 split ring r, fitted in an annular groove h'' on the hub h' of the wheel H. The wheel H is shown as having a rubber, leather, or other suitable facing h''' to increase the friction or adhesion of the wheel to the disk D. The 70 driving-belt from the source of power runs over the pulley A.

In the practice of my invention by raising the bar O the eccentric L is turned up. This raises the outer end of the lever G and lifts 75 the disk D free of the wheel H. Then by turning the handle P either to the right or left the wheel H is thrown to the right or left on the counter-shaft E. When said wheel H is located as desired, the bar O is again 80 pulled down, which brings the disk D into contact with the said wheel H, and the power is transmitted to the counter-shaft and its attached pulleys. The nearer the wheel H is to the periphery of the disk D, the greater 85 will be its speed. When said wheel H is to one side of the center of the disk D, its movement will be in one direction, and by throwing the wheel H to the opposite side of the center of the disk D the movement will be 90 in the opposite direction. In this manner the machine operated can be quickly and easily reversed. The eccentric L will lock itself in any position in which it may be placed, and thus hold the disk D to or from the wheel H 95 and avoid the necessity of constantly holding the operating-bar O with the hand when the apparatus is in motion.

While I have shown and described a system of levers for actuating the brush-wheel, 100 I do not desire to confine myself to such arrangement, as there are many machines to

- which my device can be advantageously attached, and wherein a single lever or a screw can be adapted to engage with the brush-wheel, so as to regulate the speed of the machine and cause a retrograde movement of the parts. Again, in machines where a reverse movement of parts is not desired my invention can be applied for merely changing the speed.
10. What I claim as my invention is—
1. A counter-shaft, a brush-wheel mounted on the counter-shaft and adapted to have longitudinal movement thereon, a pulley provided with a disk on one of its sides and an elongated turned hub upon its opposite side, an eccentric having an arm fixed thereto, a vertical bar having a lateral lever attached thereto, a rod with a yoke connecting said lateral lever of the vertical bar with the brush-wheel, a lever secured to the outer end of the hub of the above-mentioned pulley and adapted to raise and lower said pulley, and an arm on the upper side of said eccentric

and connecting the same with the lever that operates said disk, substantially as shown 25 and described.

2. In an apparatus for the transmission of power, a pulley provided with a disk, a brush-wheel, an eccentric, an arm rigidly secured thereto, a vertical bar attached to said arm and having a lateral lever attached thereto, a rod and a yoke connecting the lateral lever of the vertical bar to the brush-wheel, a lever adapted to raise and lower the aforesaid pulley and disk, and an arm connecting said 30 lever with the eccentric, substantially as shown and described.

In testimony whereof I affix my signature, in presence of two witnesses, this 3d day of January, 1890.

EDWIN E. PORTER.
